UNITED STATES PATENT OFFICE.

ALBERT H. STEBBINS, OF LOS ANGELES, CALIFORNIA.

VIBRATORY EXERCISE TABLE.

Application filed July 23, 1924. Serial No. 727,713.

To all whom it may concern:

Be it known that I, ALBERT H. STEBBINS, a citizen of the United States, residing at Los Angeles, in the county of Los Angeles and State of California, have invented an Improvement in Vibratory Exercise Tables, of which the following description, in connection with the accompanying drawings, is a specification, like characters on the drawings representing like parts.

This invention relates to a vibratory table for stimulating and exercising the human body.

It is known that the circulation of the blood and the action of the muscles may be stimulated in any portion of the body, by applying a vibratory device to the portion of the human body it is desired to treat, and small, portable, vibratory devices are now in extensive use.

It is found that the entire human body may be benefited by subjecting it to a rapid vibratory force, and the present invention, therefore relates to a simple and inexpensive construction of an exercise table adapted to support a person in a lying position, and provided with mechanism for moving the table back and forth rapidly in the direction of its length with vibratory effect.

Although the vibratory table of the present invention is adapted to support a person in a lying position, the person undergoing a vibratory treatment may assume a sitting or inclined position upon the table if it is desired to reduce the vibratory effects upon certain portions of the body, and the vibratory effect upon portion of the person may also be reduced by placing a soft pillow or air cushion under the person's head or body.

To secure the most effective or beneficial treatment, the table should move back and forth in the direction of its length and should be given a short but rapid movement, and it may be desirable to move the table more energetically in one direction than the other to impart a progressive vibratory movement to the table, which progressive movement may be employed to promote the flow of blood either toward or away from a person's head.

One important feature of the invention resides in novel means for supporting the exercise table for vibratory movement in the direction of its length.

Another feature of the invention resides

in the means for imparting the vibratory movement to the table.

Other features of the invention and novel combination of parts in addition to the above will be hereinafter described in connection with the accompanying drawings which illustrate good, practical forms thereof.

In the drawings:

Fig. 1 is a side elevation of a vibratory exercise table constructed in accordance with the present invention.

Fig. 2 is a top plan view of the supporting frame with the table indicated by dotted lines.

Fig. 3 is an end view of Fig. 1.

Fig. 4 is an enlarged side view of the operating eccentric and associated parts.

Fig. 5 on a reduced scale is a side elevation of modified construction of a vibratory exercise table.

Fig. 6 on an enlarged scale is a sectional view of the table supporting means of Fig. 5; and,

Fig. 7 is a sectional view of the eccentric shaft and the eccentric operated sheave of Fig. 5.

In the construction shown in Figs. 1 to 4 inclusive, a supporting frame 10 is provided with upwardly extending, semi-rigid posts 11 which support the table 12, six of these posts being shown. The posts 11 as shown each consists of spaced bars 13 having laterally extending portions 14 at their ends which are secured by bolts 15 to the frame 10 and table respectively. The construction of the posts 11 is such that while they possess sufficient rigidity to remain in an upright position and support the table under operating condition, they at the same time are sufficiently flexible to yield laterally to permit the table to move back and forth a short distance in the direction of its length.

The person undergoing vibratory treatment may lie flat upon the table 12 as shown in Fig. 1, or may assume an inclined or sitting position, depending upon whether the entire body or only a portion thereof is to be subjected to the vibratory movement, and the person's head may rest upon a pillow 16 which may comprise an air cushion. A cable 17 stretched between the upstanding brackets 18 may be provided at each side of the table 12 to assist in retaining the person in place upon the table.

The means for moving the table 12 back and forth with a short rapid movement may be variously constructed, and as shown in Figs. 1 to 4 inclusive consists of a spring 19 for yieldingly moving the table in one direction and of an eccentric operated means for alternately pulling the table in the opposite direction. One end of the spring 19 is secured to a hook fastened to the under face of the table, and the other end of the spring engages a hook at the upper end of an inclined rod 20 extending upwardly from the supporting frame 10, and the tension of the spring 19 may be varied by rotating a hand wheel 21 having threaded engagement with the lower end of the rod 20. A bowed rod 22 having its ends journaled in blocks 23 upon the supporting frame is provided to hold the upper end of the rod 20 elevated, and an intermediate portion of the rod 22 has a depression 24 (see Fig. 3) in which the rod 20 rests.

The table 12 is moved in opposition to the spring 19 by a flexible pitman or strap 25, one end of which is secured to the table at 26, and the opposite end is secured to a yoke 27 having a central opening to receive the eccentric 28 upon the shaft 29. The opposite ends of the shaft 29 are journaled in blocks 30 supported by the brackets 31 secured to and extending upwardly from the frame 10. A sheave 32 is secured to the shaft and is driven by a belt 33 operated by the electric motor 34. As the eccentric 28 rotates in the yoke 27 it alternately pulls the pitman in the direction of its length to move the table 12 in a left-hand direction, and, as the pitman is moved in the opposite direction by the eccentric, the table is permitted 40 to move in a right-hand direction under the pull of the spring 19. The pitman 25 preferably is made flexible so that it will bend, in case it is moved in a right-hand direction by its eccentric more rapidly than the table is moved by the spring 19.

From the foregoing it will be seen that the table supporting and operating means described is simple and inexpensive to construct and that it is strong and durable, and, 50 since the vibrating table is moved back and forth through a short distance, the semi-rigid posts 11 support the table in a very satisfactory manner.

In Figs. 5 and 6 a modified means is shown for supporting the table 12 for vibratory movement, consisting of coiled springs 35, one end of which is seated in a plate 36 secured to the supporting frame 10, and the other end of the spring is seated in a plate 37 secured to the under face of the table 12. Each spring may be maintained under a desired tension by a bolt 38 connecting the plates 36 and 37, and the bolt has a head 39 retained in a socket 40 of the upper plate, and a sleeve 41 surrounding the bolt

is confined in a socket 42 of the lower plate. The tension of the springs 35 is varied by adjusting the nuts 43 upon the bolts 38. The supporting springs 35 and bolts 38 permit the table a limited movement in the direction of its length.

A somewhat different means from that shown in Figs. 1 to 4 inclusive is disclosed in Fig. 5 for operating the table. In Fig. 5 the table is pulled in a right-hand direction by a spring 44 having one end secured to the hook 45 and the other end secured to the adjustable bolt 46, and is pulled in the opposite direction by a cable 47. The cable has one end secured to the table at 48 and its opposite end is adjustably secured to the supporting frame at 49. An intermediate portion of the cable 47 passes around the sheave 50 mounted upon the eccentric 51 of a rotating shaft 52 which shaft is driven by a belt 53 engaging the sheave 54. As the eccentric 51 rotates it moves the sheave 50 so that it alternately pulls and slacks off the cable 47 to move the table 12 in a left-hand direction and then release it to move in a right-hand direction under the action of the spring 44.

In each of the table operating means shown, the table is moved by a spring in one direction and by positively actuated means in the opposite direction, and as a result the movement imparted to the table may be more energetic in one direction than the other to impart a progressive vibratory movement to the table, which movement may be utilized to promote the flow of blood either toward or from the person's head, depending upon whether the person's head is placed at one end of the table or the other.

What is claimed is:

1. A vibratory exercise machine, comprising in combination, a table mounted for movement back and forth in the direction of its length and constructed to support a person in a lying position, yielding means for moving the table in one direction, a flexible pitman for pulling the table in the opposite direction and constructed and arranged so that it will bow or bend under longitudinal pressure to avoid sudden change of direction of table movement under a pushing action of the eccentric, and an eccentric for alternately pulling the pitman to move the table in the direction of its length with vibratory effect.

2. A vibratory exercise machine, comprising in combination, a table mounted for movement back and forth in the direction of its length and constructed to support a person in a lying position, means for vibrating the table more energetically in one direction than the other to stimulate the flow of blood lengthwise of the person being treated, including a spring for pulling the table in one direction, a flexible pitman for

pulling the table in the opposite direction, and constructed to bend or bow to avoid sudden change in the direction of the table movement, and a rotating eccentric for alternately pulling the flexible pitman in the direction of its length to actuate the table with vibratory effect.

3. A vibratory exercise machine, comprising in combination, a supporting frame having upwardly extending semi-rigid posts, a table constructed to support a person in a lying position and secured to the upper ends of said posts and supported thereby for a limited back and forth vibratory movement,

means for vibrating the table more energetically in one direction than the other to stimulate the flow of blood lengthwise of the person being treated, including a flexible connection for pulling the table in one direction and adapted to bend or bow under lengthwise pressure, an eccentric for actuating the flexible connection to alternately pull the table in the direction of its length and then release it, and a spring for pulling the table in the opposite direction. 15 20 25

In testimony whereof, I have signed my name to this specification.

ALBERT H. STEBBINS.
